UNITED STATES PATENT OFFICE.

JOHN BERGSTEN, OF NEW YORK, N. Y.

BRUSH.

1,360,077.

Specification of Letters Patent. Patented Nov. 23, 1920.

Application filed February 4, 1919. Serial No. 274,896.

To all whom it may concern:

Be it known that I, JOHN BERGSTEN, a subject of the King of Sweden, and a resident of the city of New York, borough of the Bronx, in the county of Bronx and State of New York, have invented a new and Improved Brush, of which the following is a full, clear, and exact description.

The object of the invention is to provide a new and improved brush arranged to permit of readily and quickly assembling the parts and to allow of conveniently replacing a worn brush body by a new one. Another object is to form a brush body of an inexpensive material by using the heretofore wasted bark of the balsa (*Ochroma lagopus*).

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the brush;

Fig. 2 is a cross section of the same with part of the handle shown in elevation; and

Fig. 3 is an enlarged sectional side elevation of the same on the line 3—3 of Fig. 1.

The brush body 10 may be made of any suitable material, preferably, however, of layers of the prepared bark of the balsa, with the fibers of the layers extending lengthwise, as plainly indicated in Fig. 1, the fibers acting similarly to the bristles now generally used in brushes employed for painting and the like. The rear or back portion 11 of the body 10 is clamped between two clamping plates 12 and 13 provided at the sides with flanges 14 and 15 overlapping each other and engaged by a pivot pin 16 extending between the plates from one side thereof to the other. By the arrangement described the plates 12 and 13 are mounted to swing so that the forward portions of the plates clampingly engage the back portion 11 of the brush body 10.

The handle 20 of the brush is provided with a head 21 made wedge shape and pushed between the rear portions of the clamping plates 12 and 13 so as to spread the said rear portions of the clamping plates

apart and thereby cause the front portions of the said clamping plates to firmly clamp the back 11 of the brush body 10 in position. The forward edge of the head 21 is provided with a groove or notch 22 adapted to engage the pivot pin 16 thus limiting the inward movement of the head 21 between the clamping plates 12 and 13. It will also be noticed that by the arrangement described the inward movement of the brush body 10 is limited as the rear edge of the back 11 abuts against the front edge of the head 21 of the handle 20. The forward edges 25 and 26 of the clamping plates 12 and 13 are preferably curved inward, as plainly indicated in Figs. 1 and 2, to insure a firm bite into the faces of the brush body to securely hold the latter in position between the clamping plates especially as the edges 25 and 26 tend to compress the brush body intermediate the ends thereof, as will be readily understood by reference to Fig. 2.

In order to render the bark of the balsa serviceable for forming the brush body, it is necessary that such bark is softened by steaming the same to allow of removing the tough outer skin and to permit of readily splitting a sheet of a desired thickness with a view to form thinner sheets or layers superimposed to provide the brush body 10 as above explained.

The brush is especially serviceable for use in cleaning kitchen sinks and the like.

Having thus described my invention, I claim as new and desire to secure by Letters Patent:

1. A brush, comprising a pair of flat clamping plates having their entire sides bent to form elongated right angular flanges overlapping each other, a pivot pin extending between the plates approximately midway between their ends and through the overlapping flanges, whereby the plates are pivoted together and the flanges at opposite sides are connected, a brush body of straight length fibers extending between the plates in front of the pivot pin, and a handle having a flat wide wedge shaped head extending between the plates in rear of the pivot pin.

2. A brush, comprising a brush body, a pair of flat clamping plates having their sides bent to form approximately right angular overlapping flanges, a pivot pin extending between the said plates approxi-

105

110

mately midway between the ends of the plates, the said pivot pin passing through the said flanges and pivotally connecting the plates and connecting the flanges at opposite sides together, the back portion of the said brush extending between the said plates in front of the pivot pin, and a handle having

a wedge-shaped head extending between the plates in the rear of the said pivot pin, the said head having a notch in its forward edge 10 engaging the said pivot pin the latter forming a stop for the said brush body.

JOHN BERGSTEN.
